DESIGN.

F. A. SEIFERT & E. D. NELLIS.
HEATING STOVE.

No. 18,766.

Patented Nov. 27, 1888.

UNITED STATES PATENT OFFICE.

FRANK A. SEIFERT AND EMERY D. NELLIS, OF ST. LOUIS, MISSOURI,
ASSIGNORS TO THE BRIDGE AND BEACH MANUFACTURING COMPANY,
OF SAME PLACE.

DESIGN FOR A HEATING-STOVE.

SPECIFICATION forming part of Design No. 18,766, dated November 27, 1888.

Application filed September 13, 1888. Serial No. 285,345. Term of patent 14 years.

To all whom it may concern:

Be it known that we, FRANK A. SEIFERT and EMERY D. NELLIS, of St. Louis, Missouri, have jointly invented and produced a new and original Design for a Heating-Stove, of which the following is a full, clear, and exact description, reference being had to the accompanying engravings, forming part thereof, in which the newly-designed stove is shown in perspective.

10 This design consists partly in the special configuration of the entire construction and partly in the special ornamentation appearing upon the stove body, substantially as herein-after more fully set forth.

15 The stove-body A, at its lower front, is extended forward to form the hearth B, and it is supported by the legs C, two of which are arranged at the rear corners, respectively, of the body A and the other two at the front corners, respectively, of the hearth. A leaf, c, appears upon the legs, and the hearth is finished smooth. The lower portion, a, of the body A is carried up in a substantially-rectangular prismatic form. Upon its front appears 20 a system of ornaments consisting of radiating forms a' a' a' a' and leaf ornaments a³ a³ a³, alternately arranged, and at the front corners of the body portion a are pilasters a⁴ a⁴, having a leaf, a⁵, substantially as shown. Upon 25 the door D, at the end of the stove-body, is a leaf, d. The upper portion, a⁶, of the stove-body, viewed in front elevation, widens upward, as shown, and the top E of the stove, which rests upon the portion a⁶, is crowned, 30 as shown, and the structure terminates at the top with the urn F. Strap-work a⁷, terminating at the upper end in a scroll, a⁸, appears upon the front of the stove portion a⁶, near the ends respectively thereof, and in the central 35 portion of the front are panels having what may be conventionalized leaf ornaments a⁹.

a⁹, substantially as shown. The edge e of the top E is smooth, and the central portion of the top is in the form of open-work diaper e', and in each square thereof is a fleur-de-lis, e². 45

We claim—

1. In a design for a heating-stove, the body herein shown and described, the same consisting of the lower portion having the rectangular prismatic form and the upper portion widening upward and covered with the crowned top, and having the superimposed ornamentation representing the radiating forms a' a' a' a' and the leaf ornaments a³ a³, alternately arranged, the pilasters bearing the leaf, the strap-work, and the leaf ornaments a⁹. 50

2. In a design for a heating-stove, the front door herein shown and described, the same consisting of the superimposed ornamentation representing the radiating forms a' a' a' a' and the leaf ornaments alternately arranged. 55

3. In a design for a heating-stove, the top herein shown and described, the same consisting of the superimposed ornamentation representing open-work diaper having the fleur-de-lis. 60

4. The design for a heating-stove herein described and shown, the same consisting of the body extended to form the hearth and supported by the legs, arranged as described, and having the crowned top, said body having its lower portion of a rectangular prismatic form and its upper portion widened upward, and said body, legs, and top having the described superimposed ornamentation. 70

75 Witness our hands this 22d day of June, 1888.

FRANK A. SEIFERT.
EMERY D. NELLIS.
